HANGERS FOR USE IN PROCESSING
PHOTOGRAPHIC PRINTS

Joseph H. De Lacy, Park Ridge, Ill.

Application November 17, 1947, Serial No. 786,400

5 Claims. (Cl. 95—100)

1

The invention relates to hangers for use in processing photographic prints.

One object of the invention is to provide a hanger for processing paper photographic prints in a tank, which will retain prints of different sizes substantially flat during their immersion in a solution.

Another object is to provide a hanger for processing photographic prints in a tank which includes gripping devices which hold the prints by point-contacts of minimum area on their sensitized face.

Another object is to provide a hanger whereby the prints will be retained substantially flat by the weight of one of the holding devices during the expansion of the paper which results from saturation.

Another object of the invention is to provide a hanger for use in processing photographic prints in a tank, which is simple in construction, adapted for prints of different sizes, can be easily loaded, and is efficient in use.

Other objects will appear from the detail description.

The invention consists in the several novel features hereinafter set forth and more particularly defined by claims at the conclusion hereof.

In the drawings: Fig. 1 is a perspective of a hanger embodying the invention. Fig. 2 is a central vertical section. Fig. 3 is a vertical section illustrating the hangers in a tank.

The invention is exemplified in a hanger which is adapted to be suspended in a tank which preferably includes a compartment 10 for a developer solution, a compartment 11 for a fixer solution, and a compartment 12 for washing-water, into which the hangers with the prints may be successively submerged. This hanger is usable for processing prints in a tank which possesses advantages over processing them in a tray.

Each hanger comprises a frame which includes a pair of vertical outer legs 14 which are provided with lateral extensions 15 to rest on the rim of the tank to support the hanger with the print in suspension above the bottom of the tank; upwardly convergent inner legs 16 which terminate at the center of the hanger in a loop 17 to provide a handle for manipulating the hanger; and angular lower connecting members 18 between the lower ends of legs 14 and 16. Legs 14, 16, loop 17 and members 18 are preferably formed of a single strip of wire.

A cross-bar 20 extends between the upper portions of legs 14 and has its ends 21 lapped on and

2

soldered to said legs to form a stiff upper cross-connection for the frame. Bar 20 is formed of sheet metal and provided with an integral horizontal flange 22 along its upper edge which indexes the upper edge of the print. Legs 16 and members 18 stabilize the lower portion of the frame and also prevent the print from falling through the frame while it is being loaded. A lower cross-bar 24 is freely movable vertically on outer legs 14, is formed of sheet metal, and is provided along its lower edge with a flange 24a and with integral loops or eyes 24b which extend around legs 14 to slidably connect the bar 24 to the frame. Eyes 24b are elongated to freely guide bar 24 vertically so that it will drop by gravity when the hanger is suspended vertically and also to permit a limited longitudinal movement of said bar.

A gripping device for the upper margin of the print is mounted on a fixed upper bar 20 and a similar gripping device for the lower margin of the print is mounted on the freely slidable lower bar 24 so that the lower bar acts as a weight for holding the print under a predetermined degree of tension and holding it flat during suspension of the hanger in the tank. The upper gripping device comprises a plate 26 which is soldered to bar 20 and legs 16 adjacent handle 17 and is provided with ears 27; a plate 28 which is provided with ears 29; a pivot-pin 30 which extends through ears 27 and 29; a bar 31 of wire having its straight central portion soldered to pivoted plate 28 and extending along the flange 22 of fixed bar 20, and provided with helical terminals 32 with pointed ends 33 which are adapted to contact with the front face of bar 20 to grip the margin of the print and hold it parallel to the flange 22 of bar 20; and a coil spring 33 around pivot-pin 30 for urging the pivoted plate 28 and bar 31 to press terminals 32 toward the front of bar 20 for gripping the upper margin of the print. The lower gripping device is mounted on slidable bar 24 and is adapted to grip the lower margin of the print so that bar 24 will be suspended by the print and the weight of said bar and gripping device will exert a predetermined tension on the print and in its plane while the hanger is suspended in the tank. This lower gripping device comprises: a plate 36 which is soldered to the back face of bar 24, and provided with ears 37; a pivoted plate 38 which is provided with ears 39; a pin 40, pivotally connecting ears 36 and 39; a gripping member 41 formed of wire and soldered to plate 38, and provided with helical terminals 42 with pointed ends for engaging the print; and

a coil spring 43 around pin 49, for causing the margin of the print to be gripped between terminals 42 and bar 24.

The outer ends of angular members 18 of the frame are adapted to limit the downward movement of the slidable bar 24 away from fixed bar 29, and the lower ends of said members act as a guard for preventing the lower bar 24 from being inadvertently struck or displaced by any object, such as the bottom of the tank. The eyes 24b on slidable bar 24 are elongated to permit limited longitudinal movement of said bar, and prevent binding between said bar and legs 14 in the event that the print is not accurately co-related in the gripping devices. Bars 29 and 24 are perforated to permit the solution to flow there through. The metal used in the parts is of the type which is resistant to photographic solutions. The angular legs 16 are disposed closer to the longitudinal center of bar 24 than the terminals 42 so that when the hangers are positioned in side-by-side relation in the tank, these legs will contact the straight portion of bars 41 so to prevent contact of the gripping devices with the sensitized face of a print in an adjacent hanger and so that the helical terminals 42 will not interfere with the placement and removal of the adjacent hangers into and out of the tank.

In the use of the hanger, it is held horizontally while being loaded. The upper margin of the print, with its sensitized face up and its other face resting on legs 16, is inserted between terminals 32 of the upper gripping device and bar 29 along flange 22, while the pivoted plate 28 is depressed against the force of spring 33. When plate 28 is released one margin of the print will be securely gripped in the frame, with contact on the sensitized face only at the points on the ends of the helical terminals 32. During insertion of the print into the gripping device, the helical terminals will guide the print into position so it will be gripped as closely as possible to its edge and so that there will be minimum contact with the sensitized face of the print. Next, the opposite edge of the print will be similarly inserted and gripped between the terminals 42 of the lower gripping device and bar 24, the latter being freely slidable on legs 14 for such insertion of prints of different sizes. The loaded hanger is then ready for suspension in the developing solution in compartment 10, and is supported vertically therein by extension 15 on the frame which hold the frame above the bottom of the tank so that the print will not be affected by any sediment in the bottom of said compartment. During the development of the print, its saturation will cause the paper to expand and the weight applied vertically to the print by the bar 24 and the gripping device thereon will apply a predetermined but not excessive tension to keep the print substantially flat. This is of importance in the processing of paper prints. After the paper has become saturated, its tear-strength is reduced. If the frame with the print is moved transverse to the faces of the print in the solution, the print is free to bow or flex between the upper and lower gripping devices because the lower gripping device is free to rise when the pressure becomes sufficient to overcome the weight of bar 24 and said device. If the print is not accurately centered in the frame at the upper gripping device, the limited free longitudinal movement of bar 24 permitted by eyes 24b, prevents any binding between legs 14 and bar 24. After the print has

been developed in compartment 10 it can be successively transferred to compartments 11 and 12 for fixing and washing. The frame is readily adapted for use in processing prints of different sizes within a desired range, for example, a print *a* of the size shown in full lines in Fig. 1 and a print *a'* indicated by dotted lines, all of which will be held under tension by the gravity of the lower bar 24. The upwardly convergent legs 16 provide clearance for the hand in manipulating the lower gripping device.

The invention exemplifies a hanger for use in processing photographic prints, which is efficient in use, simple in construction and adapted for prints of different sizes.

The invention is not to be understood to be restricted to the details described since these may be modified within the scope of the appended claims without departing from the spirit and scope of the invention.

Having thus described the invention, what I claim as new and desire to secure by Letters Patent is:

1. A hanger for photographic prints during fluid treatment comprising a frame provided with suspension means and a cross-bar and a device for gripping a margin of the print, including a gripper bar of wire pivotally supported on the bar and provided with helical end portions for guiding the print into position for gripping and terminating in points for spot contacting the print, and spring means for urging the points to grip the print between the bar and said spots.

2. A hanger for photographic prints during fluid treatment, comprising: a frame provided with suspension means; a cross-bar provided with a face adapted to be engaged by the back-face of the margin of the print, and a longitudinal flange for positioning the edge of the print on said face; and a spring-pressed gripper bar pivotally supported on and extending longitudinally of the cross-bar and formed of wire provided with helical end-portions for guiding the print to said face of the bar, and terminals for spot engagement with and pressing the print against said face adjacent said flange to frictionally grip the prints.

3. A hanger for photographic prints during fluid treatment, comprising: a frame provided with suspension means; a cross-bar provided with a face adapted to be engaged by the back-face of the margin of the print, and a longitudinal flange for positioning the edge of the print on said face; and a spring-pressed gripper bar pivotally supported on and extending longitudinally of the cross-bar formed of wire and provided with helical end-portions for guiding the print into engagement with said face and against the flange and having terminals for spot engagement with the print to press it against said face for frictionally gripping without perforating the prints.

4. A hanger for photographic prints during fluid treatment comprising: a frame provided with suspension means and outer side legs spaced apart longitudinally for prints of different sizes and formed of wire; inner legs of wire joined to the lower ends of the side legs, the outer side legs and inner legs; an upper crossbar extending between and fixed to the outer side legs and inner legs; a spring-pressed device on said upper crossbar for gripping the upper margin of the prints; a lower crossbar having its ends longitudinally slidably on the outer side legs and extending across the front of the inner legs; and a spring-pressed gripping device on the lower bar

for gripping the lower margin of the prints; the lower bar when the lower margin of the print is gripped thereon, being free for suspension by the print without substantial frictional resistance.

5. A hanger for photographic prints during fluid treatment comprising: a frame provided with suspension means and outer side legs spaced apart longitudinally for prints of different sizes and formed of wire; upwardly convergent inner legs of wire joined to the lower ends of the side legs, the outer side legs and inner legs and handle being formed of wire; an upper crossbar extending between and fixed to the side legs and inner legs; a spring-pressed device on said upper crossbar for gripping the upper margin of the prints; a lower crossbar having its ends longitudinally slidably on the outer side legs extending across the front of the inner legs; and a spring-pressed gripping device on the lower bar for gripping the lower margin of the prints; the lower bar when the lower margin of the print is gripped thereon,

being free for suspension by the print without substantial frictional resistance.
